PNEUMATIC-DESPATCH-TUBE SYSTEM.

983,793.

Specification of Letters Patent.

Patented Feb. 7, 1911.

Application filed August 10, 1908. Serial No. 447,665.

To all whom it may concern:

Be it known that I, FRANKLIN H. WOLEVER, a citizen of the United States, and a resident of Chicago, in the county of Cook 5 and State of Illinois, have invented certain new and useful Improvements in Pneumatic-Despatch-Tube Systems; and I do hereby declare that the following is a full, clear, and exact description thereof, reference being 10 had to the accompanying drawings, and to the letters of reference marked thereon, which form a part of this specification.

This invention relates to improvements in pneumatic despatch tube systems and refers 15 more specifically to means for economizing the power used in operating the system.

The invention consists in the matters hereinafter set forth and more particularly pointed out in the appended claims.

20 In the drawings: Figure 1 is a diagrammatic view with parts broken away of a portion of a despatch tube system equipped with my improvements. Fig. 2 is a horizontal view, partially in elevation and partially in 25 section, of the cashier's sending terminal. Fig. 3 is a cross section taken on line 3—3 of Fig. 2. Fig. 4 is a cross section taken on line 4—4 of Fig. 2. Fig. 5 is a cross section taken on said line 4—4 of Fig. 2, with parts 30 shown in changed positions. Fig. 6 is a cross section taken on line 6—6 of Fig. 2. Fig. 7 is a side elevation of a modified form 35 of cashier's sending terminal. Fig. 8 is a cross section taken on line 8—8 of Fig. 7. Fig. 9 is a detail of a relief valve in the 40 exhaust pipe connecting the main vacuum trunk line of the system with one of the loops extending between the cashier's station and a salesman's station.

45 As shown in the drawings, 10 designates the cashier's sending tube line and 11 the salesman's sending or return tube.

12 designates as a whole a combined receiving and delivery terminal located at the 45 salesman's station 13, arranged to deliver a cartridge downwardly therefrom to the salesman's desk. Said terminal is of familiar form and embraces a sending gate 14 through which cartridges are delivered to 50 the salesman's sending tube, and an automatically closing gate 15 which closes an opening in said terminal through which cartridges are delivered from the terminal. The terminal 12 is arranged to afford com-

munication between the cashier's and salesman's tubes at the salesman's station 13 and to thereby constitute a closed loop through which an air current is maintained in the proper direction to transmit the cartridges therethrough by connection of the loop at 60 one point with a vacuum inducing means. The sending and delivery terminals of said tubes are normally closed and the system is sealed during periods of disuse.

18 designates, as a whole, the cashier's 65 sending terminal located at the cashier's desk 19, and 20 designates the cashier's delivery terminal located at said desk and beneath the down turned end of the salesman's sending tube. The end of the salesman's 70 tube above the delivery terminal 20 is equipped with an automatically closing, downwardly opening gate 21 which opens to permit cartridges to be delivered from the salesman's tube to said delivery terminal. 75

24 designates a pipe which is connected at one end with the delivery end of the cashier's sending tube and at its other end with a vacuum main or trunk 25.

A complete system of this character usually embraces a plurality of loops extending from a number of salesmen's stations to a single cashier's station, each loop communicating with the vacuum main by a pipe 24. Air at atmospheric pressure is admitted to 80 the loop at the cashier's sending terminal and is withdrawn from the loop through the pipe 24, whereby the air moves in one direction in one tube and in the opposite direction in the other tube. My invention 85 relates to improvements in means for admitting air to the despatch tube arranged to automatically admit air to the tube when a cartridge is inserted or introduced therein and to draw a supply of air as long as a 90 cartridge is traveling through the tube, and to automatically cut off the supply of air upon the discharge of a cartridge from the system. The despatch tube system is thus sealed during periods of disuse of the system so as to thereby economize the power required to keep in motion a column of air in 95 the tube to propel cartridges therethrough. The invention relates also to improvements in automatically operated check valves for 100 admitting air to the system and to improvements in sending terminals through which cartridges are admitted to the system. The 105

mechanism for thus controlling the admission of air to the system to carry the cartridges therethrough and to shut off the entrance of air to the system when a cartridge 5 has been delivered to its station is shown as associated with the cashier's sending terminal and also with the salesman's sending terminal, one or both of which may be employed depending upon the length of the 10 tube and other conditions. The air inlet device at the cashier's sending station is shown as being made a structural part of the cashier's sending terminal which practice may advantageously be followed, and may 15 also be varied.

The cashier's terminal embraces a tube section 30, which is jointed to the receiving end of the cashier's sending tube, and an upwardly opening trough-like receiving 20 mouth 31 arranged axially in line therewith, in which the cartridges are laid horizontally to be delivered to the tube section 30.

33 designates a movable valve or gate that is adapted to extend across the bore of the 25 tube section 30 to shut off the admission of air to the system at this point, and to be moved out of line with said section to admit a cartridge to the terminal. The said valve or gate, as herein shown, consists of a 30 flat disk which swings in the direction of its plane toward and from its closed position. The tube section is slotted at its top and at one side to receive said valve and is formed at its unslotted portion with a curved seat 35 groove to receive the marginal part of the valve disk, which latter is shown as made circular in its part within the tube section. Guide wings 35, 35 rise from the tube in line with the slit therein to guide the valve in 40 its swinging movement. The said valve is fixed at one side of the tube section to a rock-shaft 37 which is parallel with the axis of said section and is mounted in lugs 38, 39 extending laterally from the tube. The 45 said valve is herein shown as fixed to the rock-shaft 37 between washers 40, 40 fixed to the shaft, the outer end of the valve being clamped between said washers. The valve fits closely between the guide wings and in 50 the slit of the tube section which receives the same to prevent the leakage of air past the same into the system. It may be made of, or faced with, leather or other suitable material.

55 The valve is held normally in its closed position across the tube section 30 by means of a torsional spring 42 which surrounds the rock-shaft 37 and is attached at one end to the shaft and provided at its other end 60 with a lateral extension 43 which engages a part stationary with said lugs 38, 39, consisting, as herein shown, of a web 44 made integral with said lugs. The rock-shaft 37 is provided with a crank arm 45 by which 65 the valve may be opened against the action

of said spring. When the valve is thus opened the tube section 30 of the receiving terminal is unobstructed to permit the free passage of a cartridge thereinto.

Means are provided for locking the valve 70 open until the cartridge passes fully into the terminal, so constructed as to automatically release the valve as soon as the cartridge has passed the valve. The means herein shown for effecting this result is 75 made as follows: The rock-shaft is provided on its end remote from the crank arm with a cam disk 50 having at one side thereof an abrupt tooth or projection 51 which is approached from the concentric portion of the 80 disk's periphery by a peripheral cam surface 52. 54 designates a horizontally swinging trigger lever which is located at one side of the tube section and is pivoted between its ends on a stud 55 projecting laterally from 85 the said section. The forward end of said lever is pressed in contact with the periphery of the locking cam 50 by means of a suitably applied spring 56, herein shown as consisting of a U-shaped leaf spring that is interposed between the adjacent lateral side of the tube section 30 and the inner face of the 90 said lever. Thus said spring normally holds the trigger lever engaged with said cam, and when said cam is turned in the direction 95 indicated by arrow in Fig. 4, which occurs when the rock-shaft is rocked to open the valve 33, the forward end of the lever swings behind the tooth or projection 51 of said locking cam and locks said rock-shaft 100 in position to hold the valve open. The said trigger is acted upon by the cartridge as it passes through the tube section 30 to release the same from said locking cam. As herein shown, the rear end 58 of the trigger 105 lever extends through an opening 59 in the adjacent side of the tube section into the path of a cartridge passing through said section. The inwardly projected end 58 of said trigger lever 54 is located at such 110 distance from the valve 33, relatively to the length of a cartridge, that the cartridge will have fully passed said valve before it engages said trigger lever. Upon engagement of the cartridge with the end 58 of the 115 said trigger lever, said lever is swung on its pivot to release the same from the tooth or projection 51 of the locking cam, whereupon the spring 42 acts to automatically swing the valve or gate 33 in its 120 closed position. The said trigger lever is inclosed in a casing 60 which prevents the leakage of air into the despatch tube through the opening 58. As herein shown, the lug 39 constitutes one end of said casing.

125 Means are provided for supplying air to the system behind the cartridge, after the closing of a sending gate, for a sufficient length of time to insure the delivery of the cartridge to its destination. In order to 130

effect this result I provide a valve which opens upon the insertion of a cartridge into the tube and which remains open under the usual working pressure of the system, or at 5 a time when a cartridge is being transmitted through the despatch tube, and which is automatically closed by atmospheric pressure acting against the same after the cartridge has been discharged 10 from the system, thus sealing the system. One of the air admission valves herein shown constitutes part of, or is associated with, the cashier's sending terminal and is made as follows: The tube section 30 of 15 said sending terminal is provided at its lower side with an opening 65 which is inclosed by a short, downwardly extending branch 66 joined to the said tube section. 67 designates a valve disk which has a rising and falling movement and is adapted 20 when in its uppermost position to close the opening of said branch 66. The said valve disk 67 is fixed to the upper end of a vertically reciprocating valve stem 68 that has 25 guiding engagement with a tube 69 which is fixed to the lower horizontal member 70 of a yoke 71 attached to and suspended from the branch 66. As herein shown, the guide tube 69 is exteriorly screw-threaded for 30 screw-threaded engagement with a part 73 carried by the horizontal member of said yoke to afford vertical adjustment of the valve. The valve 67 and its stem may be suitably weighted so that it will close only 35 at a predetermined difference of pressure on the upper and lower sides thereof. As herein shown, the said valve stem is screw-threaded at its lower end and carries one or more nuts 74 which may provide the 40 weight required. A suitably applied spring may also answer the purpose of normally holding the valve open. The valve 67 is thus adjusted, relatively to the normal working pressure of the system, and will 45 not close under the influence of the ordinary working pressure of the system. That is, when a cartridge is passing through the despatch tube, the valve remains open to admit air to the tube behind the cartridge after 50 the sending gate is closed and until the cartridge is delivered to its proper destination. After the cartridge has been discharged from the system, however, velocity of the moving column of air is increased and its 55 pressure is decreased to such extent that atmospheric pressure acting on the lower side of the valve will close the latter, thus sealing the part of the system or loop which the valve controls. Thereafter, and until an- 60 other cartridge is delivered to the system at one of the stations, the air in the idle loop is dead or practically stationary so that power is not required to keep in motion a current of air in the idle or empty loop. 65 The operation of a system embodying my

improvements may be briefly stated as follows: When a cartridge is to be admitted to the salesman's sending terminal the sending gate 33 is opened through the medium of the crank arm 45 of the rock-shaft 37. The 70 said sending gate is locked in its open position by the trigger lever 54 and the locking cam 50, and the gate is closed by the action of the spring 42 when the cartridge passes into engagement with the inner end of the 75 trigger lever in a manner to release the lever from the locking cam. The inrush of air to the despatch tube, which occurs upon the opening of the gate 33, lowers the pressure in the tube to such extent that the check 80 valve 67 drops from its seat at the end of the branch 71 whereby air is admitted to the tube through the valve opening 65 behind the cartridge after the cartridge passes said opening. Air is admitted through said open- 85 ing to the despatch tube to propel the cartridge to its intended destination, and so long as the cartridge remains in the tube, and when the cartridge is discharged from the terminal 12 at the salesman's station the ve- 90 locity of the air in the tube is increased and its pressure is decreased to such extent that atmospheric pressure acting against the lower side of the check valve 67 has the effect to close said valve and thereby seal the 95 tube until another cartridge is delivered thereto. Likewise, upon delivery of a cartridge to the sending terminal 12 at the salesman's station, the opening of the sending gate 14 and the in-rush of air to the tube has 100 the effect of increasing the pressure in the loop or tube, whereby the check-valve 67 is opened to admit air to the tube behind the cartridge. Said check valve remains open and air is supplied to the tube until the cartridge 105 is discharged from the tube to the terminal 20 at the cashier's station, whereupon the valve is closed to seal the tube or loop. Thus it will be seen that the admission of air to the tube through said check valve to trans- 110 mit a cartridge through the tube is controlled wholly by the pressure within the despatch tube, said tube being opened to admit air thereto upon the insertion of a cartridge into the tube, and the tube is auto- 115 matically closed and sealed upon the discharge of a cartridge from the tube. I am, therefore, enabled to accurately admit the required volume of air to the tube to trans- 120 mit a cartridge therethrough without the employment of a timing device and to effect the transmission and delivery of the cartridge regardless of variations of the load and speed of the cartridge or variations of the power. In other words, the mechanism 125 herein shown automatically times the transmission and delivery of the cartridge independently of the load and speed of the cartridge and of variations of power, the dis- 130 charge of the cartridge from the system ab-

solutely controlling the admission of the propelling air. It will be observed that the opening controlled by the check valve has the full capacity of the tube so as to admit 5 the required volume of air to the tube without restriction, and that the adjustment provided for the valve, including the adjusting sleeve 69 and the means for weighing or otherwise restraining the closing movement of the valve, enables me to accurately 10 adjust the valve to different lengths of transit tubes. The valve itself automatically times itself to varying loads and like conditions.

15 In Fig. 7 I have shown a modified form of the sending terminal 75. The terminal shown in Fig. 7 is provided with a flaring mouth 76 which is closed by a gate 77 that is pivoted at the upper side of the mouth 20 on a pivot pin 78 carried by a lug 79 made integral with the terminal fitting, as herein shown. The said gate is provided with a finger piece 80 by which it may be opened. The gate, being hinged at its upper side, 25 may be closed by gravity or said closing movement may be assisted by the aid of a suitably applied spring, if desired. The arrangement of the terminal is such that the gate does not fully close when released, 30 but engages a yielding stop which operates to hold the gate partially open so long as a cartridge is in the despatch tube. Said gate is closed by atmospheric pressure acting on the outer side thereof when the pressure is reduced in the tube, due to the discharge of a cartridge therefrom. The yielding stop herein shown is made as follows: 35 85 designates a pin that is arranged horizontally beneath the mouth of the terminal 40 and is mounted in a horizontal sleeve that is fixed to a lug 87 depending from said terminal 75. The said pin is provided with a head 88 against which the lower side of the gate strikes when swung to its closing position. The pin is held normally projected 45 for engagement of the head thereof with said gate to hold the latter in a partially open position by means of a spiral expansively acting spring 90 which surrounds said 50 pin and is interposed between the head 88 and the head 86. A suitable shoulder, as the nuts 91, are carried by the ends of the said stop pin and engage the rear end of the sleeve to limit the forward movement of the 55 stop pin. In the operation of a system including this type of terminal, the gate 77 is opened to the upper dotted line position to admit a cartridge to the terminal. Thereafter the gate is released and it swings 60 against the stop pin to the position indicated by the lower dotted lines. In this position the gate is held open sufficiently to admit air to the tube behind the cartridge to effect the transit of the cartridge therethrough and its 65 delivery therefrom. As soon as the cartridge

has reached its destination and has been discharged from the tube the pressure in the tube is lowered and the superior atmospheric pressure acting against the outer side of the gate 77 acts to completely close the 70 gate against the action of the spring 90 and seal the system at this point.

The salesman's despatch or transit tubes may, if desired, be provided at the salesman's stations with sending gates of the 75 types hereinbefore described having means for automatically controlling them by the transit through or discharge of a cartridge from the despatch tube.

In despatch tube lines of considerable 80 length I provide an air inlet valve adjacent to the salesman's sending terminal in order that inlet of air to the tube behind the cartridge may be effected with greater despatch when a cartridge is inserted into the tube 85 at the salesman's station, and also to avoid the effect of frictional loss in the tube, which in a long line, may tend to close a single inlet valve. Thus the salesman's sending tube is shown in Fig. 1 as provided with a lateral 90 inlet valve opening 66^a closed by a check valve 67^a like the valve 67 heretofore described.

I have provided a manually operable device for releasing the valve 33 in the event 95 that it should be opened and a cartridge not inserted into the terminal. The releasing device which I have shown consists of a plunger 92 which extends through a sleeve 93 fixed in the side wall of the casing 60, 100 the plunger being arranged to engage the spring pressed end of the trigger lever to swing it out of engagement with the cam tooth 51. A spring 94 holds said plunger retracted while permitting said plunger to be 105 yieldingly pressed toward said trigger lever.

In a despatch tube system of the type herein shown the main vacuum trunk 25 may be connected with a large number of loops, each having at each end a sending 110 and delivery terminal. In such systems the power plant and pumping mechanism are arranged to adapt themselves to the expected demands of the system, there being a suitable governor mechanism for this purpose, as is usual. In the ordinary or normal use of such a system having a large number of loops it is not likely all of the loops connected with the vacuum trunk line will either be in operation or out of use at 115 the same movement. Therefore, there will usually be a fairly constant demand for power. In order to provide against the disuse or inactivity of all or nearly all parts of the system at any given time when the power plant is in operation I may provide a relief valve 95 in each of the pipes 24 between each operating loop of the system and the vacuum trunk line 25, so arranged as to admit air to said loop in case of an abnor- 120 125 128

mal tension of the air, due to a relatively large number of inactive loops or sets of tubes. The use of such a relief valve prevents too great an attenuation of the air and great stress on the power plant.

The relief valve which is shown in Fig. 9 comprises a branch 97 extending laterally from the pipe 24 and opening at its inner end into the said pipe and at its outer end to the atmosphere. The said branch is adapted to be closed at its inner end by a valve 98 which is attached to a valve stem or rod 99 extending outwardly through a suitable guide opening in a winged guide 100 located 15 and fixed in the branch 97. The valve is normally held to its seat by means of a spring 101, herein shown as a spiral expansively acting spring, which surrounds the stem 99 and is interposed between the guide 20 100 and a nut or other suitable shoulder 102 at the outer end of the valve stem. Upon a predetermined decrease of pressure in the system, due to the causes mentioned, said valve will be opened and permit the leakage 25 of air into the system to relieve the low pressure and avoid unnecessary stress on the power plant.

I claim as my invention:—

1. In a pneumatic despatch tube system, 30 the combination with a despatch tube adapted for connection at one end with vacuum producing means and provided at its other end with a sending terminal closed by a gate, of an unobstructed branch tube connected with said terminal at a point inside 35 the gate and affording an unrestricted passage for air to the despatch tube, and formed at its lower edge to provide an annular valve seat for engagement with a 40 valve and a flat disk valve the upper flat face of which is adapted for engagement with said seat for closing the open end of said branch tube, said valve being supported by means located below said branch tube, 45 and adapted to be opened by gravity when the terminal gate is opened to insert a cartridge into the terminal and to be closed by atmospheric pressure upon the discharge of a cartridge from the despatch tube.

2. In a pneumatic despatch tube system, 50 the combination with a normally sealed despatch tube, means for exhausting air from the tube, and a sending terminal through which cartridges are inserted into the tube, 55 of a valve device between the terminal and the discharge end of the tube for admitting air to the tube behind a cartridge to propel the same through the tube, comprising a branch communicating with the tube and 60 opening to the atmosphere, a check valve adapted to close said branch, said valve being subjected at one side to the pressure in the tube and at its other side to atmospheric pressure and arranged to be directly acted 65 upon by variations of pressure on the oppo-

site sides thereof to open and close the same, and means for adjusting said valve toward and from said branch.

3. In a pneumatic despatch tube system, 70 the combination with a despatch tube adapted for connection at one end with vacuum producing means and provided at its other end with a sending terminal closed by a gate, of an unobstructed branch tube connected with the terminal at a point inside 75 the gate and affording an unrestricted passage for air to the despatch tube, a flat disk valve for closing the open end of the branch tube, a stem extending downwardly from said valve, a support for said disk valve 80 embracing a guide sleeve arranged axially below said branch tube, and means for adjusting said sleeve toward and from the open end of the branch tube.

4. In a pneumatic despatch tube system, 85 the combination with a pair of normally closed despatch tubes extending between and connecting two stations and having their receiving and delivery terminals at respective opposite stations, a connection between 90 said tubes at one station and a vacuum pipe connected with the delivery terminal at the other station, of air inlet valves connected one with each of the sending terminals, said valves being normally closed and arranged 95 to admit air to the tubes behind the cartridges upon the insertion of the cartridge into the despatch tube, the valves being subjected at their inner sides to the pressure in the tubes and at their outer sides to atmospheric pressures and arranged to be directly acted upon by variations of pressure on opposite sides thereof to open and close the same.

5. In a pneumatic despatch tube system, 105 the combination with a despatch tube and an exhaust pipe connected with one end of the tube for exhausting air therefrom, of a receiving terminal at the other end of the tube provided with a gate for closing the same 110 and arranged to be opened to admit a cartridge to the terminal, means tending to urge said gate to its closing position, means for locking the gate in its open position, 115 means located within the receiving terminal at a point just inside of said gate for releasing the locking means to permit the gate to be returned to closing position, and a valve-controlled air inlet passage for supplying air to the tube behind the cartridge after 120 said gate is closed.

6. In a pneumatic despatch tube system, 125 the combination with a despatch tube, and an exhaust pipe connected with one end thereof for exhausting air therefrom, of a receiving terminal through which cartridges are admitted to the tube comprising a gate which normally closes the terminal, said gate comprising a flat plate or disk which swings in its plane and the tube being 130

- slotted to receive the valve, a rock-shaft to which said valve is fixed, a spring acting on the rock-shaft to normally hold the gate in its closed position, means acting on the 5 rock-shaft for locking the gate in its open position against the action of the spring, and means controlled by the passage of a cartridge through the terminal for releasing said locking means.
- 10 7. In a pneumatic despatch tube system, the combination with a despatch tube, and an exhaust pipe connected with one end thereof for exhausting air therefrom, of a receiving terminal through which cartridges 15 are admitted to the tube comprising a gate which normally closes the terminal, a rock-shaft to which said gate is fixed, a spring acting on the rock-shaft to normally hold the gate in its closed position, a locking pro- 20 jection on said rock-shaft, and a spring-pressed trigger lever adapted to engage said locking projection to lock the gate in its open position, one end of said lever extending into the terminal and into the path of 25 the cartridges.

8. In a pneumatic despatch tube system, the combination with a despatch tube, and an exhaust pipe connected with one end thereof for exhausting air therefrom, of a receiving terminal through which cartridges 30 are admitted to the tube comprising a gate which normally closes the terminal, a rock-shaft to which said valve is fixed, a spring acting on the rock-shaft to normally hold the gate in its closed position, means acting 35 on the rock-shaft for locking the gate in its open position against the action of the spring, a trigger in the terminal controlled by the passage of a cartridge through the terminal for releasing said locking means, and a manually operative device for releasing said locking means.

In testimony, that I claim the foregoing as my invention I affix my signature in the presence of two witnesses, this 8th day of 45

August A. D. 1908.

FRANKLIN H. WOLEVER.
